(57) **CLAIM**

The ornamental design for a tensioner with teeth, as shown and described herein.

DESCRIPTION

FIG. 1 is a front view of the present invention.

FIG. 2 is a back view of the present invention.

FIG. 3 is a top end view of the present invention.

FIG. 4 is a bottom end view of the present invention.

FIG. 5 is a left side view of the present invention.

FIG. 6 is a right side view of the present invention; and,

FIG. 7 is a perspective view of the present invention.
